UNITED STATES PATENT OFFICE.

CHARLES J. VAN DEPOELE, OF CHICAGO, ILLINOIS.

ELECTRIC RAILWAY.

SPECIFICATION forming part of Letters Patent No. 324,899, dated August 25, 1885.

Application filed January 10, 1885. (No model.)

To all whom it may concern:

Be it known that I, CHARLES J. VAN DE POELE, a citizen of the United States, residing at Chicago, in the county of Cook and State 5 of Illinois, have invented certain new and useful Improvements in Electric Railways, of which the following is a specification, reference being had to the accompanying drawing.

The present invention relates to improvements in means for manipulating and controlling the propelling and retarding mechanism of any railway that is wholly or partially operated by the use of electric apparatus; and it consists in so constructing and applying 15 the propelling motor and a series of electro-magnetic brakes that by reversing the brushes of the motor with respect to the line of commutation and closing the brake-circuit upon the motor-circuit, the armature will be forcibly rotated by the momentum of the vehicles 20 to be stopped, and the motor thereby converted into a generator, the current from which will pass through the coils of the brake magnet, energizing the same and applying the brakes 25 to the wheels with a force proportionate to the speed of the train. The same arrangement may be utilized upon railways operated by steam or horse power, the motor being arranged and operating in precisely the same 30 manner, except that no connections with any external source of electricity will be necessary. By the insertion of a variable resistance between the motor and the coils of the brake-magnet the resistance of said circuit can 35 be varied so as to allow the field-magnets of the motor to become more or less energized, and thereby to increase or decrease the retarding action of the armature itself, which, as will be evident, can be used as a brake 40 without the aid of anything more than a resistance-circuit closed upon the motor-circuit, which resistance should be variable, in the first instance, for obvious reasons.

The accompanying drawing is a view in elevation of apparatus embodying my invention, in which A represents the track or roadway; B, a car carrying the motor C, which is connected to the wheels C' of said car by a belt, C², which passes around a pulley, D, secured 45 on the axis of the armature of the motor, and also around pulleys D', secured to the axles of the wheels C'. D² D³ are contact-brushes lead-

ing to the source of electricity. E is a second car, and both are provided with an electro-magnetic brake, consisting of the solenoid F, 55 having a movable soft-iron core or plunger, f, suitable brake-shoes G G, bearing against the wheels H, and the intermediate connections, g g, extending between and properly pivoted to the plunger f, the said shoes G being suitably supported by hangers J or other well-known means.

From the binding-posts P and N of the motor the conductors 1 and 7 and 8, which latter also include the variable resistance W and a 65 manual-switch, 2, extend to the contacts K L, which may be double, as shown, or simply a strip of the desired length. A similar pair of contacts, M O, are located in proximity to the contacts K L, and between the two sets is located a suitable switch, which, in this instance, is shown as having two arms, Q R, centrally pivoted and connected by cross-bar S, suitably insulated. The brushes D² D³ make contact with a suitable source of electricity and connect with contacts M O through conductors 70 3 4 with contacts T U, located in the path of the switches Q R. (See Patent No. 285,858, October 2, 1883.) The coils of the solenoids F are connected with contacts M O through conductors 5 6.

The contacts being arranged as described, or according to any of the many other equally convenient plans that will readily suggest themselves to the practiced electrician, I am 85 enabled to place the switch in position to close the brake-circuit through the motor-conductors 1, 7, and 8, contacts K M L O, conductors 5 6, and the solenoids F, thereby cutting out the source of supply-contacts T 90 U, when, by reversing the positions of the commutator-brushes Y with respect to the line of commutation by means of a suitable lever, Z, the car B being in motion, the motor, which is of the type which is converted into 95 a generator, a current is sent to the solenoids F, which at once raise their cores f and the devices thereto attached with a force proportionate to the speed of the car. By shifting the switch from the contacts K M L O to the 100 source of supply T U and thence to contacts M O, the solenoids F will receive current direct from the main current and the brakes be applied without aid from the motor, said mo-

tor being then either cut out entirely, as indicated, or receiving current through independent switching devices. (Not shown.) When the switch is in the position shown—viz., sup-
5 ply-contacts T U, and the motor-contacts K L—the main current is passing directly through the said motor, which can then be put in forward or backward movement, as de-
sired, by moving the brushes Y through the
10 handle Z.

The variable resistance W, which is prefer-
ably located in the motor-circuit, is adapted
15 to be included therein to any extent or cut
out entirely, enabling it to be used both to
regulate the power of the motor while prop-
elling the cars and to control the current in
the brake-circuit when said motor is acting
20 as a generator. It is also extremely useful
when the brake mechanism is absent or out
of order, for in such case by closing the brake-
circuit in any well-known manner or by other-
wise closing the motor-circuit the resistance
25 W will be closed upon the motor-circuit. The
positions of the commutator-brushes are then
to be shifted, and more or less of the resist-
ance placed in the generating-circuit so cre-
ated, which, by allowing the field-magnet coils
30 and armature of the motor to become ener-
gized to a greater or less extent, will offer
greater or less resistance to the rotation of its
armature by the wheels of the moving car.
The variable resistance is also extremely useful
35 in controlling the power of the solenoids,
for, by means thereof, the current passing
through said solenoids can be regulated to a
nicety and at the same time more or less (the
desired) resistance can be maintained in the
generator-circuit.

Instead of shifting the brushes on the mo-
40 tor the current in the field-magnets can be
reversed, with respect to the armature, thus
changing the motor to a generator, without
departing from the spirit of my invention.

What I claim is—

45 1. In a system of electric railways, the com-
bination of a motor receiving current from a
source of electricity as long as it is necessary
to propel the train, with proper means for
cutting out the motor from said source of elec-
50 tricity when it shall be necessary to stop

said train, and means for reversing the brushes
of and thereby converting the motor into a
generator while under headway, and for clos-
ing the motor-circuit upon one or more elec-
tric brakes, when the current produced by
said motor, acting as a generator, will actuate
said brakes and stop the train, substantially
as set forth.

2. In electric railways, the combination, with
a motor, a car, and means for supplying a cur-
rent to the motor for propelling said car, of
an electro-magnetic brake and connections
between the coils of said brake and the binding-
posts of the motor, and means, substan-
tially as described, for cutting off the propel-
ling current and for carrying current generated
by forcible rotation of the armature of the
motor to the brake circuit, as described.

3. In electric railways, the combination of
a generator, a car, means for forcibly rotating
the armature of the generator by the momen-
tum of the car, an electro-magnetic brake or
series of brakes, and connections between the
coils of said brake or brakes and the brake-
circuit, means for shifting the commutator-
brushes, and suitable switches for carrying
the current produced by the forcible rotation
of the armature of the generator to the brake-
circuit, as set forth.

4. In electric railways, the combination, with
a motor, a car, means for supplying current
to the motor for propelling the car, an electro-
magnetic brake or series of brakes, and connec-
tions between the coils of said brake or
brakes and the binding-posts of the genera-
tor, and an adjustable resistance included in
the brake-circuit, of means for reversing the
commutator-brushes and suitable switches for
cutting out the propelling current and for
carrying the current generated by forcible
rotation of the armature of the motor, acting
as a generator, to the brake-circuit, as set
forth.

In testimony whereof I affix my signature
in presence of two witnesses.

CHARLES J. VANDEPOELE.
